UNITED STATES PATENT OFFICE.

PIUS J. ROTH, OF TARRYTOWN, NEW YORK.

FAUCET ATTACHMENT FOR BARRELS.

SPECIFICATION forming part of Letters Patent No. 247,852, dated October 4, 1881.

Application filed February 12, 1881. (No model.)

To all whom it may concern:

Be it known that I, PIUS J. ROTH, of Tarrytown, in the county of Westchester and State of New York, have invented an Improved 5 Bung-Lining and Faucet Attachment for Barrels, of which the following is a specification.

Figure 1 is a vertical longitudinal section of my improved bung-lining for barrels; Fig. 2, a front view of the same, showing it in place 10 on the barrel-head; Fig. 3, a front view of the same when disconnected from the barrel-head and open for use. Fig. 4 is a top view of the same.

This invention relates to a permanent attachment for barrels as a means of connecting thereto the faucets whenever desired.

The invention consists, principally, in providing the bung-lining, which is permanently secured in the barrel-head, with a revolving 20 spigot between a supporting-shoulder and projecting ears, and also with a screw-thread in front, by means of which it can be connected to the faucet, the screw-thread being, by preference, an external screw-thread to admit the 25 attachment of an ordinary faucet.

I am aware that heretofore barrels have had bung-linings made of metal; but such bung-linings, if provided with valves within the recess in front of the barrel-heads, required expensive caps as means of securing them in place. My invention differs from these former 30 devices in providing the bung-lining with a revolving spigot between a supporting-shoulder and supporting-ears, so that it can be attached to the barrel without the necessity of an external cap. The spigot is independently 35 turned to admit the liquor to the faucet or shut it off from the same, as may be desired.

In the accompanying drawings, the letter A 40 represents the tubular body of the bung-lining. It is made of brass or other suitable metal, and provided with an external shoulder, *a*, which is adapted to bear against the head B of the barrel, as shown. The inner end of the lining 45 A is or may be perforated, as shown at *b* in the drawings, to serve as a strainer. The outer

end of the lining A has a screw-thread applied, as shown at *d* in Fig. 4, to receive the faucet. The lining A is attached to the barrel by putting it through the bung-hole until the shoulder *a* strikes the face of a recess provided for its reception in the barrel-head, and suitable screws are then put through projecting ears *e*, with which the outer part of the lining A is provided. These ears *e* bear against the face 55 of the barrel-head, as is clearly shown in Figs. 2 and 4.

In front of the shoulder *a*, and back of the threaded portion *d* and of the ears *e*, is put through the tube A a spigot, C, by means of which the tubular passage through the tube A may be closed or opened at will. The outer end of this spigot is made square, as in Fig. 4, or of such other form as will permit it to be turned by a removable key. In fitting this 60 attachment to a barrel, I sink the spigot into the head by providing a proper recess, *g*, in the latter for this purpose, as is clearly shown in Fig. 1, so that in transportation the spigot will not be exposed to contact with other things, 65 and therefore not liable to be opened or otherwise brought out of order. When the barrel is being transported or not used, a suitable cap, *h*, may be screwed upon the outer end of the lining A, and when the barrel is to be used 70 this cap *h* is removed and a suitable faucet attached. Yet the faucet cannot be used until the owner of the key sees fit to open the spigot C. This attachment also permits the ready 75 discharge of superfluous gas from the barrel. 80

What I claim, and desire to secure by Letters Patent, is—

The tubular bung-lining A, having threaded portion *d*, projecting ears *e*, and shoulder *a*, in combination with the spigot C, which is fitted 85 through the lining A back of the ears *e* and in front of shoulder *a*, substantially as described.

PIUS J. ROTH.
